C. C. SILVERTON.

WINDOW REFRIGERATOR.

APPLICATION FILED APR. 30, 1918.

1,280,109.

Patented Sept. 24, 1918.

Fig. 1.

UNITED STATES PATENT OFFICE.

CLAUDE C. SILVERTON, OF NEW YORK, N. Y.

WINDOW-REFRIGERATOR.

1,280,109.

Specification of Letters Patent. Patented Sept. 24, 1918.

Application filed April 30, 1918. Serial No. 231,585.

To all whom it may concern:

Be it known that I, CLAUDE C. SILVERTON, a citizen of the United States, residing in the city, county, and State of New York, have invented certain new and useful Improvements in Window-Refrigerators, of which the following, taken in connection with the accompanying drawings, forms a complete and exact description thereof.

10 My invention relates to an improvement in window refrigerators, and it is an object thereof to provide a plain and economically constructed window refrigerator that may readily be applied to the sill or ledge of a 15 window, but which will not in any way interfere with the raising and lowering of the sash thereof.

It is a further object of my invention to provide a refrigerator of the character designated which when in position on the window ledge will be elevated therefrom to eliminate corroding of the box due to moisture collecting beneath the same. This feature has another advantage in that by providing ventilation openings in the bottom 25 and sides of the box a good circulation of air throughout the box will be had at all times.

Another object of the present invention is 30 to provide a box which may be moved to the interior of the room, and the window closed when it is desired to remove articles therefrom, without disturbing the means by which the box is secured to the window ledge.

A still further object of my invention is 35 to provide rails secured to the window ledge to hold the box in place thereon, the cover of the box being carried by the rails and forming in effect a continuation thereof on which the box is slid when it is desired to move the same to the inside of the window.

And a still further object is to provide a 40 double roof for the refrigerator spaced from each other to protect the box against the direct rays of the sun.

In the accompanying drawings wherein I have illustrated the preferred embodiment 45 of my invention—

50 Figure 1 shows my device in perspective.

Fig. 2 is a part sectional elevation of my device in place upon a window ledge.

Fig. 3 shows in elevation the box moved

to the inside of the window and the window closed; and

Fig. 4 shows in elevation a portion of the track.

Referring now to the drawings in detail, 5 1 designates the body of the box which is preferably constructed of metal and suitably 60 coated with any of the well known materials to protect it against the elements. The box is open at the side designated 2. The roof of the box, designated 3, is preferably set at an angle as shown, to shed rain, snow and so forth, which otherwise would collect on the same. To the roof I secure a plate 4 of suitable material, spacing the same from the roof proper by legs 5 or other suitable means, this plate acting as an awning to 65 effectively intercept the sun rays which otherwise would beat directly upon the roof of the box. This awning is slightly larger over all than the roof of the box, that is to say, at both ends, and the rear wall of the 70 box so that rain and so forth running off the awning will fall clear of the box. It will be understood, of course, that if the awning is not used the roof 3 will be made so as to extend over the rear wall and the two ends 75 of the box. The bottom of the box, which I have designated 6, is shaped to form a channel member 7 for a purpose which will be described presently, and has flanges 8 extending beyond the ends of the box. 80

To hold the box in position on the outside 85 of the window, I have provided a frame or rail structure comprising end members 10 formed of metal strips set on edge and bent over to form channel structures 9 to receive 90 the flanges 8 on the box bottom already referred to. These members 10 have a cut out portion 11 at their forward ends so that a portion of the members will rest upon that portion of the window ledge designated 15 95 while the remaining portion will rest on the portion designated 16. By forming these rail members in the manner shown, not only will the box 1 be always maintained elevated above the window ledge to eliminate moisture collecting beneath the box to corrode the same, but there will always be a good bearing surface for the rails even though the width of window ledges may vary. To secure the members 10 in place, I 100 provide ears or lugs 12 at the forward ends 105

thereof when the cut out portions 11 are formed, these ears extending substantially at right angles to the members 10, and having holes 13 therein, through which I pass 5 screws 14 or other fastening means which are screwed into the portion 16 of the window ledge. Braces 17 and 18 are secured to the strips 10, one at the front ends thereof and the other at the rear, the latter, the 10 strip 18 acting as a stop or abutment to prevent the box 1 from being pushed off the rear ends of the rails. The strips 17 and 18 are of a lesser depth than the members 10 so that by providing ventilation holes such as 15 30 and 31 in the bottom and sides of the box, respectively, a good circulation of air throughout the box is insured.

To the bracing member 17 I hinge a cover 19 for the box, this cover at its end adjacent 20 the hinges being bent over to form a flange 20 braced as designated at 21, this flange abutting the member 17 when the cover is in open position, as shown in Fig. 3. The underside of the cover when the latter 25 is open rests on the window sill, which would probably be sufficient support for it, but in addition to that I have provided a metal strip 22 set on edge which I secure to the underside of the cover, which member 30 will rest upon the inside portion 23 of the window sill when the cover is open, thus insuring sufficient support for the cover when the box is resting on it. To the inside of the cover I secure a rail member 24 T-shaped in cross section, adapted to coöperate with the channel member 7 of the bottom of the box. When the box is moved to the inside of the window it will travel in the rail 35 members 10 until the channel member 7 engages the rail 24, after which the box is guided thereby and will slide inwardly on its cover to the position shown in Fig. 3. It will be noticed that the box is so dimensioned that when it stands on its cover the 40 window may be closed behind it, the window at this time acting as a reinforcement for the cover. By making the member 24 T-shaped in cross section and having the channel member 7 shaped accordingly the box 45 may be pulled out beyond the end of the cover 19 yet will not tip off.

To the end walls of the box I secure strips 50 32 against which the cover abuts when closed, being held in closed position by a 55 latch 25 secured to the cover, the catch of which engages a member 26 on the roof of the box or which may be a flange formed by bending over the front edge of the roof.

For supporting shelves within the box, I 60 provide brackets designated 27 welded or otherwise suitably secured to the inner side of the end walls of the box, and supporting members 28, T-shaped in cross section and having their rear ends suitably secured to 65 the rear wall of the box, while their front

ends are supported by a member 29, having one end secured to the channel member 7 and its other end to the roof of the box. By this construction I obtain a much better circulation of air throughout the box than though I had provided a partition in place of the member 29. The cross section of the members 28 is important also in that it prevents the shelves placed thereon from sliding off endwise. 75

While I have illustrated the preferred embodiment of my invention, it is obvious that various changes in details of construction might be made therein without departing from the spirit and scope of my invention. 80 For instance, if desired for sanitary purposes, the corners of the box and the rails too, for that matter, could be rounded off to facilitate cleaning, and also other methods of fastening the rail structure to the window sill could be provided. I desire, therefore, not to be limited except by the appended claims. 85

What I claim as new and desire to secure by Letters Patent of the United States is: 90

1. In combination, a box, rails for supporting the box, and a cover for the box carried by the rails, the cover and rails co-operating so that the box may be slid along the rails and on to the cover to be supported 95 by the latter.

2. In combination, a box to be applied to a window ledge, rails resting on the window ledge for supporting the box and to maintain it elevated therefrom, and along which 100 the box is adapted to be moved toward the inner side of the window.

3. In combination a box, rails adapted to rest on a window ledge for supporting the box at the outer side of a window, a cover for the box, and coöperating with the rails when in opened position so that the box may be slid along the rails and cover to the inner side of the window. 105

4. In combination, a box, rails for supporting the box, a cover for the box, and a rail structure carried thereby and coöperating with the box to prevent lateral displacement of the latter when moving on the 110 cover. 115

5. In combination, a box, a support therefor, a cover for the box adjacent the supporting means, a rail member carried by the cover, the bottom of the box having a groove formed therein to coöperate with the rail 120 member on the cover to guide the box when slid along its cover.

6. In combination, a box, a rail structure for supporting the same, a cover for the box adjacent the rail structure for supporting 125 the box when moved off the rail structure, and a brace for the cover carried thereby and coöperating with the rail structure when in operative position.

7. In combination, a box, a supporting 130

structure therefor adapted to be mounted on a window ledge, a cover for the box adapted to support the latter when in open position, and means carried by the cover and adapted 5 to engage a portion of the window ledge when the cover is in box supporting position.

8. In combination, a box, a cover therefor, a rail member carried by the cover and adapted to coöperate with the box so that 10 the box may be moved longitudinally of the cover but may not be displaced laterally or vertically.

CLAUDE C. SILVERTON.
